(57) **CLAIM**

The ornamental design for a package for computer cable, as shown and described.

DESCRIPTION

FIG. 1 is a perspective view of a package for computer cable of the present invention;

FIG. 2 is a front elevation view thereof;

FIG. 3 is a rear elevation view thereof, the broken line representing a score mark for a folding tab;

FIG. 4 is a left side elevation view thereof;

FIG. 5 is a right side elevation thereof;

FIG. 6 is a top plan view thereof, the bottom plan view being a mirror image; and,

FIG. 7 is cross sectional view taken along line 7—7 in FIG. 2.
